CLAIM

The ornamental design for a grille with sensor cleaners, as shown and described.

DESCRIPTION

FIG. 1 is a top, front, left-side perspective view of a grille with sensor cleaners;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed broken lines depict portions of the grille with sensor cleaners that form no part of the claimed design.

1 Claim, 7 Drawing Sheets
